UNITED STATES PATENT OFFICE.

NICHOLAS J. YONKER, OF MUSKEGON, MICHIGAN.

FURNACE.

Application filed February 20, 1922. Serial No. 537,906.

To all whom it may concern:

Be it known that I, NICHOLAS J. YONKER, a citizen of the United States, residing at Muskegon, in the county of Muskegon and State of Michigan, have invented new and useful Improvements in Furnaces, of which the following is a specification.

The present invention relates to furnaces; and its object is to provide casings for such furnaces as are employed for heating dwellings and other buildings by hot air, which casings shall have means whereby the heated air may be directed to the several air vents of the casing and the air pipes leading therefrom as may be desired.

This object is attained by, and the invention finds preferable embodiment in, the structure hereinafter particularly described in the body of this specification and illustrated by the accompanying drawing, in which:

Figure 1 is a top plan view (partially broken away to show the interior) of a furnace casing and the air pipes leading therefrom;

Figure 2 is a side view of the upper portion of the same, partially sectioned on line 2—2 of Figure 1;

Figure 3 is a sectional view of a portion of the same taken on line 3—3 of Figure 1, and showing a portion of one of the vanes;

Figure 4 is a sectional view of the same taken on line 4—4 of Figure 3;

Figure 5 is a view of the central portion of the interior of the top of the furnace casing, showing the swingable mounting of the vanes;

Figure 6 is a view of the inner portion of one of the vanes; and

Figure 7 is a sectional view of the same taken on either line 7—7 of Figure 6.

In the embodiment of the invention chosen for illustration by the drawing and for detailed description in the body of this specification, the furnace casing, designated generally 1, has a top portion, designated generally 2, having spaced vents through which the heated air is delivered to the air pipes 3, 4, 5, 6, 7 for distribution to the various parts or rooms of the building to be heated. This top portion 2 is depressed at its center, extending cross-sectionally in an inclined direction from its center upwardly toward its side, as particularly shown in Figure 2. A plurality of vanes 8, 9, 10, 11, 12 (corresponding in number with the hot-

air pipes) are swingably mounted on a vertical post 13, substantially concentric with the vertical central axis of the furnace casing. Such mounting may be provided by bending tongues 14 at the inner edge of the vane, so as to encircle the post 13, as shown in Figure 7, the tongues of the several vanes being stepped interrelatively to each other, as particularly seen in Figure 5, and the vanes being held on the post as by a nut 15. Springs 16 extending outwardly from the free ends of the vanes and slidably contacting in an annular groove 17 in the casing top's interior serve to hold by friction the vanes in any position to which they may be swung.

When the furnace is being constructed, it is equipped with a sufficient number of vanes corresponding to the number of hot-air pipes leading therefrom, and these vanes are swung to such interrelative positions as will direct a predetermined amount of heated air to one pipe and a predetermined (greater or less) amount to another pipe, as their capacities may require, all as illustrated in Figure 1. Thereupon the vanes may, if desired, be permanently fixed in such adjusted position; or the vanes may remain swingable for future adjustment as may be desired, in which case they may be swung either way by their pins or handles 18 extending through narrow slits 19 in the side of the casing's top.

The invention being intended to be pointed out in the claim, is not to be limited to or by details of construction of the particular embodiment thereof illustrated by the drawing or as hereinbefore described.

I claim:

In a furnace casing, a top having an annular groove, spaced slits and spaced air vents in its side, vanes swingably mounted concentrically with the vertical axis of the furnace casing and adapted to direct currents of air to the vents respectively; means carried by the vanes and in frictional contact with the inner surface of the annular groove for holding the vanes in adjusted position, and means carried by the vanes and projecting through the slits for adjusting the vanes.

In testimony whereof I have hereunto set my hand at Grand Rapids, Michigan, this 15th day of February, 1922.

NICHOLAS J. YONKER.
